UNITED STATES PATENT OFFICE

2,609,162

REEL

Hilyard C. Howsam, Chicago, Ill.

Application October 4, 1946, Serial No. 701,340

6 Claims. (Cl. 242—124)

1

My invention relates to reels, and more particularly to a reel upon which wire or cable or other strand may be wound.

There are reels of the prior art which employ wood for the head of the reel and, in some instances, they employ plies of wood to make up heads of more uniform strength. The heads generally are spaced apart by a hub and the two heads are held against separation by bolts which pass through the two heads and through the hub. It has been the practice in some cases to provide washers beneath the heads of the bolts, as well as beneath the nuts threaded on the other ends of the bolts, which washers bear flatwise against the side of the grain of the wooden heads to distribute the pressure over a greater area. In some cases a flat washer is merely set against the outer surface or set in a flat bottomed counterbore around the bolt head. Sometimes a stepped washer is used set partly into said counterbore, but the result is the same. With such construction tightening up of the nuts upon the washers crushes the wood by pressure on the side of the grain. Even if plywood is employed to form the heads, the pressure exerted on the side of the grain of the outer ply of a head tends to crush and break that ply or otherwise damage it, thus weakening the reel. An undesirable consequence of such bearing against the side of the grain of the wood is that the bolts can never be kept tight. If the wood dries out it shrinks crosswise of the grain and the bolts become loose. If they are now drawn tight, expansion of the wood by subsequently acquired moisture will cause crushing of the grain with consequent looseness upon again becoming dry. A further disadvantage of certain prior constructions is that the heads of the bolts and the nuts protrude from the sides of the heads, thereby making them more inconvenient in use and storage.

It is an object of my invention to provide means for applying and distributing the stress of the bolts upon the end grain of the wooden or plywood heads, which means will not split, or otherwise damage the wooden head. In attaining this goal, I employ a novel type of stress distributor at either end of the bolts for joining the heads, which distributors are formed with a taper so as to be drawn into tapered sockets in the heads and to exert the major part of their pressure against the end grain of the wood, or plies of wood constituting the heads, instead of exerting their pressure against the flat grain of the wooden heads.

It is a further object of my invention to render

55

2

more easy and secure the joining of the heads of the reel to the hub by bolts, and to this end I provide a stress distributor in which the head of the bolt will be seated in a mating recess so that relative rotation between the bolt and said distributor is impossible. By employing longitudinal ridges, fins or grooves in the surface of the stationary distributor, it is possible to prevent the said distributor from turning once it is seated against the end grain of the head. It is then only necessary for the person assembling the reel to thread on the nut at the other end of the bolt, since the end of the bolt having the bolt head is retained against rotation. By making the bodies of both distributors of the same general shape, the recesses in the opposite heads of the reel may both be cut alike by the same tool.

The rotatable distributor which I provide also serves as a nut for the bolt since it is internally threaded. It has a smooth, generally conical exterior, so that it may readily be threaded on to the bolt and into the tapered bolt hole in the head. As the distributor rotates within the bolt hole and exerts pressure against the end grain of the head, it tends to turn the end grain in the direction of rotation. Consequently, when the flange of the threaded distributor is drawn down to the desired depth in the face of the head and upon the bolt, the turned end grain acts as a locking means to prevent rotation of the distributor in the opposite direction. This locking effect may be accentuated by cutting or casting one or more longitudinal notches or grooves in the surface of the distributor, which notches are so formed as by undercutting one side of the groove as to ratchet over the grain of the wooden head when the distributor is threaded on to the bolt, but which catch hold of the wood fibers when rotated in the opposite direction.

The distributors are preferably both substantially conical in shape, although the stationary one may be of any preferred tapered non-circular shape. At their wider ends the distributors are flared outwardly in such a fashion as to form a flangelike portion which serves in some degree as limiting means to prevent penetration of the distributor into the head beyond a certain point, and mainly to bind and finish the grain of the wood about the outer end of the recess.

Since the distributor at both ends of the bolts penetrate the heads, leaving only their flared out or flanged ends on the surface of the heads, the reels may be more closely packed against each other and will be less likely to interfere with each other.

Other objects, uses and advantages of my invention will become apparent from the following description, when taken with the drawings in which:

Figure 1 is a cross sectional view, taken on the lines 1—1 of Figure 2, of a reel embodying my invention;

Figure 2 is a side elevation of the reel shown in Figure 1;

Figure 3 is a sectional view, taken on the line 3—3 of Figure 1;

Figure 4 is a sectional view, taken on the line 4—4 of Figure 1;

Figure 5 illustrates a modified form of pressure distributor;

Figure 6 represents a view similar to that of Figure 3, except that the distributor of Figure 5 is employed instead of the distributor illustrated in Figure 3;

Figure 7 is a view in elevation of another modification of the pressure distributor of my invention;

Figure 8 is a plan view of the distributor of Figure 7;

Figure 9 is an elevation of still another form of pressure distributor; and

Figure 10 is a plan view of the distributor of Figure 9.

Like reference numerals have been employed in the several views to indicate the same elements.

Referring now to Figures 1 through 4, it will be seen that the reel is indicated generally by the reference numeral 1 and comprises a pair of circular, parallel, spaced apart flat disklike heads 3 and 5, which are preferably formed of layers of plywood, said heads being spaced apart by a tubular sheet metal hub 7 and held against separation by a plurality of bolts 9, 11 and 13. Each of the heads 3 and 5 has a central aperture, such as apertures 15 and 17, in which are seated, respectively, sheet metal bearing sleeves or grommets 19 and 21 which are adapted to fit over a shaft or arbor, so that the reel may be rotated thereon. The peripheries of the heads 3 and 5 have centrally disposed rounded grooves 23 and 25, respectively, over which are placed sheet metal covers 27 and 29, respectively, which cover the peripheries and conform to their shape. As a result, the external surface of the covers 27 and 29 provide grooves corresponding to the grooves formed in the peripheries of the head. These grooves are adapted to carry a belt which may be driven to rotate the reel when it is supported upon a shaft or arbor. To secure the covers 27 and 29 in place, one edge of each is spun over and pressed into the outside surface of its head thereby to grip the same, as shown at 31 and 33, respectively. At their other edges, each of the covers fits over a portion of the inner surface of each head and has an axially extending flange, such as the flange 35 of cover 27 and the flange 37 of cover 29. The sheet metal hub 7 has a press fit over the flanges 35 and 37 and thereby holds the heads 3 and 5 against relative lateral movement and against axial movement toward each other.

The sheet metal covers 27 and 29 are each formed initially with a cylindrical flange which is of a diameter to receive the periphery of the head 3. Then the metal of the flange in register with the groove in the wood is shrunk into the groove in the periphery of the head. This may be done by spinning or by a radially acting die to fit the sheet metal into the groove. Then the outer edge of the flange is curled over the

edge as by spinning of the metal to make the raw edge bite into the surface of the wood. This provides a neat, strong and highly advantageous construction.

In order to hold the heads 3 and 5 together on the hub 7, I employ a plurality of symmetrically disposed bolts. Since each of the bolts and its associated pressure distributors are the same, a description of one will suffice for all of them. Reference will, therefore, be had to the bolt 9 which has a square head 39 and a threaded end 40. The head 39 is preferably hot forged, and need not be further finished. A pressure distributor indicated generally by the reference numeral 41, has a central aperture 42 through which the shank of the bolt 9 passes, and has a socket 43 of substantially the same configuration as the head 39 of the bolt 9, the socket being so formed in order to prevent relative rotation between the head of the bolt and the distributor. The distributor 41 is of substantially the shape of a truncated cone except that the sloping surface of the distributor flares outwardly at its base, that is, has a different rate of slope, so that the distributor is somewhat flanged at its outer or wider end. Ridges or fins 45, extending longitudinally of the axis of the distributor 41, are adapted to dig into the end grain of the head 5, so that the distributor 41 will not rotate with respect thereto.

At the threaded end 40 of bolt 9, as well as at the ends of the bolts 11 and 13, there is a distributor such as that indicated generally by the reference numeral 47. Distributor 47 is similar to distributor 41 in all respect, except for the absence of ridges, such as the ridges 45 of distributor 41, and except for the internal thread at the central aperture 49. Although the socket 51 of distributor 47 is the same shape as the socket 43 in distributor 41, it is employed not for receiving a bolt head, but for receiving the head of a wrench or driving tool, and may, therefore, assume any shape which will prevent relative rotation between it and the driving head of such a wrench or tool. It is important to note that because of their shape and application the distributors 41 and 47 both exert their pressure mainly against the end grain of the heads 3 and 5 rather than against the flat grain of said heads. Consequently, the heads, or plies of wood thereof, are much more resistant to crushing or cracking. At their wider ends or bases, the distributors 41 and 47 have flared out ends which seat upon the outer surfaces of the heads 5 and 3, and consequently against the flat grain, but these flared out portions or flanges of the distributors 41 and 47 serve as limiting means to prevent further penetration of the distributors into the tapered sockets about the bolt holes 55 and 53, respectively, in the heads 5 and 3, and do not exert excessive pressure on the flat grain of the heads or their outer plies of wood. These flared out ends act as binding flanges for the fibers surrounding the edge of the conical recess, thereby making a neat closure for the outer end of the recess and showing no gap between the distributor and the wood.

The sockets in the heads 3, 5 are all alike being cut by a revolving tool or cutter. The preferred taper of the main part of the socket and of the distributor is approximately 20° whereby the major part of the pressure on this surface is sustained by the radial thrust against the side walls of the socket. The angle of the body increases so as to shade by a rounded fillet into the

flange which has a small area of bearing upon the flat outer surface of the head. Obviously, this main angle may be varied within the teaching of my invention, since I believe it to be broadly new to use a flanged distributor of tapered shape in order to apply the pressure mainly to the end grain along the bore of the opening while at the same time binding the edges of the conical recess.

The angle of the main body part of the distributor is preferably well below 45° for softer woods and a pronounced flange is desirable. For harder woods the flange may be of less radial extent than the proportions shown in Figure 1, and the angle of the body may be substantially greater than the 20° shown. The second distributor is preferably rotatable on the threads because this provides a unique and economical connection and mode of operation in that both distributors fit into similarly formed sockets and require a minimum of metal, but I regard the principle of distribution of pressure and binding of the edges of the grain by a tapered pressure distributor to be new in this type of construction. The two distributors need not be of identical size.

The outer edge of the preferred form of distributor lies substantially flat against the side of the grain of the head and may even be slightly undercut if desired to give a finished effect. It is sufficient to bring the flange out near enough flat to gain a tight fit which leaves none of the wood fibers, cut in forming the recess, exposed. Thus the outer edge of the recess in which the distributor is seated is sealed off from the weather. Since wood expands and contracts very little in the direction of the grain by changes in moisture the distributors remain tight indefinitely.

Figure 3 illustrates how the distributor 41 is prevented from rotating relative to the head 5 by reason of its ridges 45 sinking into the grain of the wood of head 5. This prevents the bolt 9 from turning when the threaded distributor 47 is screwed on to the threaded end 40 of bolt 9, because the bolt head 39 is restrained against relative rotation within the socket 43 in the distributor 41. Since the person assembling the reel does not have to hold the heads 39 of the bolts against rotation, the assembly operation is much easier and may be performed much more quickly, and may be done by one man from one end of the device.

It may be noted more readily from Figure 4 that rotation of the distributor 47 to thread it upon the bolt 9 (the direction rotation being indicated by the arrow A) tends to direct the end grain of the wooden head 3 in the direction of rotation of the distributor, as may be seen at 51, for example. The end grain of the wood thereafter resists rotation of the distributor 47 in the direction opposite to that of the arrow A, and thereby tends to prevent loosening of distributor 47 with respect to the bolt 9. By forming the distributor 47 as illustrated it will be seen that I have combined the functions of a nut and a pressure distributor in one article and have simultaneously provided a locking means for the distributor by cooperation of its sloping surface with the end grain of the head in which the distributor seats.

Figures 5 and 6 illustrate a modified form of distributor, which is indicated generally by the reference numeral 61, said distributor differing from distributor 41 only in that grooves 63 are substituted for the ridges 45 of the distributor 41.

The edges 65 of the grooves 63 are undercut so that when the distributor 61 is drawn into the head 5, when the internally threaded distributor 47 is drawn up on the bolt 9, the edges 65 will bite into the side of that portion of the end grain which protrudes into the grooves 63, as shown at 67. Distributor 61 will, therefore, be held against rotation with respect to the head 5, and will, in turn, hold the bolt 9 against rotation with respect to the wooden head 5. It will be appreciated that other shapes than a cone could be employed for distributors 41 or 61, a pyramid, for example, being satisfactory, since the corners thereof will sink into the end grain of the wooden head to prevent rotation of the distributor with respect thereto.

The modified form of pressure distributor illustrated in Figures 7 and 8 is indicated generally by the reference numeral 71. This distributor has its smaller end 73 provided with a plurality of slots 75 preferably formed during the casting thereof. It may be done by a subsequent cutting operation. The slots may extend partly or completely through the side wall. Slots 75 extend longitudinally of the distributor and serve to divide its smaller end into sections 77 which are adapted to move radially inwardly when radial pressure is exerted on them, as, for example, when the distributor is drawn in to a bolt hole in one of the wooden heads of the reel. Distributors for cooperation with either end of a bolt may be formed with the slots 75 and will tend to grip the bolt as they are drawn into the heads of the reel.

In Figures 9 and 10 there is illustrated a form of internally threaded pressure distributor 81 which is similar to the distributor 47 of Figure 1, except that longitudinally extending notches or grooves 83 are cast or cut in its surface. It will be noted that the grooves 83 are so formed, as by providing an undercut at one side, that the edges 85 thereof will readily ratchet over the end grain of the wooden heads of the reel when the distributor is threaded on to the end of a bolt, i. e., in the direction indicated by arrow B. However, when the distributor is rotated in the opposite direction, the wooden fibres of the head will resist such movement by reason of their extending into the grooves 83. This locking action is in addition to the locking action of the end grain of the wood on the smooth surface of the distributor, as described above with respect to distributor 47.

Whether the bolt holes 53 and 55 in the heads 3 and 5, respectively, are cylindrical or somewhat conical in shape, or otherwise formed, as the internally threaded distributor 47 is threaded upon the bolt 9, the distributors 47 and 41 will be drawn toward each other and will sink into the head while pressing against the end grain of the various plies of the wooden heads 3 and 5. Distributor 41 will be drawn in axially with respect to the bolt and will not rotate by reason of the ridges 45 or equivalent irregularities in its surface, while the distributor 41 will be drawn in axially while it rotates about the bolt 9 in being threaded thereon. When distributor 47 has been threaded upon the bolt 9 to the point where the outwardly flared ends of the distributors 41 and 47 engage against the external surface of the heads 5 and 3, the heads will be firmly held against separation by the distributor 41 and 47 which will then fit snugly into the heads and will not rattle or become loose, the distributor 41 being held against rotation by its ridges 45, and the distributor 47 being

locked in position by the turned end grain of the head, which turned end grain acts ratchet-wise upon the sloping surface of the distributor as shown at 57 in Figure 4.

It is particularly to be noted that in distributing the pressure of the bolt to the plywood heads, the structure of my invention brings pressure directly upon each ply by engaging the end grain along the full length of the hole through the head. The crossing of the grain by the wood in successive plies overcomes the weakness of the tendency to split the wood which would be much more pronounced if the head had the grain running all in one direction, as is the case in a solid board. Obviously, my invention may be used with a one-piece wooden head but the tendency to split is greater.

In reference to the statements herein that the load or stress of the bolt is sustained chiefly in the end grain of the wood, it is to be noted that where a tapered recess is formed in a body of wood across the grain of the wood, the pressure of the distributor is chiefly sustained by the end grain because pressure of said distributor against the side of the grain produces yielding thereof at unit stresses far below those which the end grain will sustain. The load is thereby automatically taken by the end grain in each of the plies engaged by the distributor. I speak of applying pressure of the bolt to each of the plies of the head as the most advantageous construction. Obviously, failure to engage all of the plies does not escape my invention, as this I believe is the first structure to distribute the pressure along the length of the hole as distinguished from applying pressure flatwise to the side grain about the hole as the prior art teaches. The engaging surfaces of the distributor and of the aperture are preferably substantially surfaces of revolution. These distributors are preferably formed as zinc or aluminum base die castings.

Although I have illustrated a preferred embodiment of my invention, I do not intend to be limited to the details thereof, excepting so far as they are recited in the following claims, since certain changes may be made within the skill of the art without departing from the scope of the invention, as defined by the following claims.

I claim:

1. A pressure distributor for applying the pressure of a bolt to a wooden member such as a reel head formed of successive layers of wood, with the grain thereof crossing, which distributor is adapted to seat in a tapered aperture in the reel head and comprises a generally cone-shaped body, the angle of the main body part with respect to its longitudinal axis being of the order of 20° whereby it is adapted, under the tension of the bolt, to wedge itself into said aperture and to impart the pressure of the bolt independently to successive layers of the head and mainly to the end grain of said layers, the larger end of said distributor being outwardly flared and being adapted to seat against the outer surface of the head about the tapered aperture to seal it off.

2. The pressure distributor of claim 1 wherein the tapered surface of the pressure distributor is provided with longitudinally extending ridges for resisting turning when seated in the aperture in the reel head.

3. In combination, a wooden reel head, a bolt for applying pressure to said head substantially at right angles to the plane of said head, an aper-

ture through said head having its axis substantially at right angles to the plane of said head, said aperture having wall means tapering inwardly in the direction in which the pressure of the bolt is applied, and a tapered pressure distributor seated in said aperture, said distributor being connected with said bolt, the taper of said distributor and of said aperture being of the order of 20° causing the pressure of the bolt to be transmitted mainly to the end grain of the head along the wall means of the aperture, and said distributor having its larger end outwardly flared on a radius to a diameter greater than that of the larger end of the aperture and seating against the outer surface of the head about the tapered aperture to seal it off.

4. A pressure distributor for applying the pressure of a bolt wooden reel head, which distributor is adapted to seat in a tapered aperture in the reel head with its axis cross-wise of the grain of the head, said distributor comprising a tapered body having a surface of revolution with the angle of the main body part of the distributor with respect to its longitudinal axis being of the order of 20° and having an axially threaded bolt receiving aperture, the outer end of which is provided with a non-circular socket by which the distributor is adapted to be rotated in and wedged into the aperture in the reel head, under the tension of the bolt, to impart the pressure of the bolt mainly to the end grain of the head and to turn the end grain to form it into locking means cooperating with the surface of the pressure distributor.

5. In combination, a wooden reel head, a bolt for applying pressure to the side of said head, an aperture through said head which the bolt is adapted to enter, said aperture having wall means tapering inwardly in the direction in which the force of the bolt is applied, and a tapered pressure distributor seated in said aperture, said distributor being connected with said bolt, and the taper of said distributor and of said aperture being of the order of 20° and causing the pressure of the bolt to be transmitted mainly to the end grain of the head along the wall means of the aperture.

6. In combination, a wooden reel head, a bolt for applying pressure to said head substantially at right angles to the plane of said head, an aperture through said head having its axis substantially at right angles to the plane of said head, said aperture having wall means formed principally of end grain and tapering inwardly in the direction in which the pressure of a bolt is applied, and a rotatable pressure distributor having a taper corresponding to that of the aperture and having an external smooth surface of revolution, said distributor being threadedly connected with said bolt and being wedged into said aperture by rotation of said distributor, said tapered pressure distributor applying the pressure of the bolt principally on the end grain, and said end grain being turned by rotation of the distributor and forming locking means cooperating with the surface of the pressure distributor to resist rotation of the distributor toward released position.
